UNITED STATES PATENT OFFICE.

CREIGHTON A. LOGAN, OF BELMONT, MASSACHUSETTS.

WHIP-LOCK.

1,120,952.

Specification of Letters Patent.

Patented Dec. 15, 1914.

Application filed August 14, 1913. Serial No. 784,830.

To all whom it may concern:

Be it known that I, CREIGHTON A. LOGAN, a subject of the King of England, residing at Belmont, in the county of Middlesex, 5 State of Massachusetts, have invented certain new and useful Improvements in Whip-Locks; and I do hereby declare the following to be a full, clear, and exact description of the invention, such as will enable others 10 skilled in the art to which it appertains to make and use the same.

This invention relates to improvements in whip sockets, and particularly to locks therefor.

15 The principal object is to provide a simple structure which can be attached to the ordinary whip socket which is arranged to lock the whip in the socket, and to be opened only by those authorized.

20 Other objects and advantages will be apparent from the following description when taken in connection with the accompanying drawings.

In the drawings: Figure 1 is an elevation 25 of a whip socket showing my invention applied thereto. Fig. 2 is a vertical longitudinal sectional view through the socket and lock. Fig. 3 is a horizontal sectional view on the line 3—3 of Fig. 2.

30 Referring particularly to the accompanying drawings, 10 represents the whip socket which is provided in one side thereof and intermediate of the length, with a longitudinal opening 11. Secured to the socket and 35 arranged over the opening 11 is a housing 12, this housing having an opening 13 which is arranged in registry with the opening 11 of the socket. Extending transversely in the housing, and adjacent the opening 13 is 40 a shaft 14, which carries rigidly secured thereto a cam block 15. This block is so arranged that the enlarged or nose portion 16 thereof can be turned through the opening 11 of the socket and engaged against

45 the butt of the whip 17 disposed in the socket, to wedge the same against the opposite side of the socket and prevent unauthorized removal. On the periphery of the cam block at a point opposite the nose 16 50 are the ratchet teeth 18, these teeth being arranged to be engaged by the free end 19 of a leaf-spring 20, suitably secured within the housing. This spring has formed near

its free end a shoulder 20' under which is engaged a finger 21 carried by a transverse 55 shaft 22, this shaft also carrying a downwardly and outwardly extending member 23. A yoke-shaped resilient member 24 is secured to the top of the housing and extends downwardly over the outer end thereof and 60 has its other end 25 disposed under the bottom of the housing and provided with an elongated slot 26. A washer plate 27 is disposed over the slotted portion 25 and secured to the bottom of the housing by means 65 of a screw 28. Thus the member 24 can be moved inwardly and outwardly, the lower portion above the bottom of the housing being arranged to engage the before-mentioned member 23.

70 In the operation of the device, the shaft 14 is turned by means of a suitable thumb-piece 14' carried thereby, so that the teeth 18 will pass under the end 19 of the spring 20. When so turned, the nose 16 will pass 75 into the socket through the opening 11 and engage against the butt of the whip. The engagement of the spring with the teeth, effectively prevents the block being rotated back to the original position. To release 80 the block, the lower portion of the resilient member 24 is pushed inwardly to engage the member 23 which causes the rocking of the shaft 22 and the engagement of the finger 21 under the shoulder 20' to move the 85 spring out of engagement with the teeth 18. The block can then be rotated back to the original position, the nose 16 then being disposed within the housing.

85 In one side of the housing adjacent the outer side of the member 23 I form a key-hole slot 29 which permits of the insertion of a key for rocking the shaft and releasing the spring. When the key is used, the member 24 is locked in rigid position by tightening the screw 28, thus preventing the movement of the member 24.

90 What is claimed is:

95 The combination with a whip socket having an opening in one side, of a whip locking device secured to the socket over the opening and consisting of a cam block rotatably disposed to project through the opening in the socket, ratchet teeth formed on a portion of the periphery of the block, a leaf-100 spring mounted in the housing and engag-105

ing the teeth of the block, said spring having a shoulder adjacent the free end thereof, a transverse shaft having a radial finger engaging under the said shoulder, a second finger on the shaft extending toward the outer side of the housing, and a resilient member mounted on the housing for engagement with the second finger, to rock

the shaft and cause the finger to release the spring from the teeth.

In testimony whereof, I affix my signature, in the presence of two witnesses.

CREIGHTON A. LOGAN.
